 General Machinery Corporation, Hamilton,
 Ohio, a corporation of Delaware

Application September 18, 1934, Serial No. 744,555

14 Claims. (Cl. 113—38)

This invention relates to power presses and more particularly to presses for drawing or forming sheet metal or the like.

One object of the invention is the provision of a metal forming press having a plurality of slides adapted to carry the forming dies, the slides being operated by mechanism which is comparatively simple and of economical construction but arranged as to provide for the proper timed operation of the slides, the press being so arranged that the assembly and disassembly of the parts can be readily effected.

Another object of the invention is the provision of a press having a plurality of toggle operated slides driven from a common operating shaft so as to move in the same direction toward the work, the connections between the operating shaft and the toggle operating mechanisms of the two slides being constituted entirely of pivotally connected links and arms or levers.

Another object of the invention is the provision of a press having a slide mounted for reciprocatory movement in the press bed, the slide having a body portion which is longer than the distance between the side frame members of the press but which can be withdrawn from the press bed in an upward direction and removed through an opening provided in the press frame.

Another object of the invention is the provision of a triple action press embodying a plurality of toggle operated die slides and lower die slide all driven in a symmetrical manner from a common crank shaft, provided in the upper portion of the press, by simple driving connections constituted of pivotally connected links and arms or levers.

Other objects and advantages of the invention will be apparent from the following description, the appended claims and the accompanying drawings, in which,—

Fig. 1 is a perspective view looking at the front of a press embodying the present invention;

Fig. 2 is a rear elevation looking at the upper portion of the press;

Fig. 3 is a horizontal section taken just above the press bed on the line 3—3 of Fig. 5;

Fig. 4 is a front elevation of the lower portion of a press, shown partly in vertical section;

Fig. 5 is a central transverse section taken through the lower portion of the press on the line 5—5 of Fig. 4;

Fig. 6 is a vertical transverse sectional view taken on the line 6—6 of Fig. 2 showing operating connection between the crank shaft and the

toggle system by means of which the inner slide is operated;

Fig. 7 is a vertical section taken on the line 7—7 of Fig. 2 showing the operating connection between the crank shaft and the toggle system which operates the outer or blank holding slide;

Fig. 8 is a diagrammatic view showing the timed relationship of the slides; and

Fig. 9 is a side elevation, partly in vertical section, through the front rock shaft.

Referring more particularly to the drawings by reference numerals, 10 designates generally the frame of a power press adapted for drawing or forming metal sheets or the like. As shown herein, the press is of large size capable of forming very large sheets such as are used in the manufacture of automobile bodies. The frame 10 includes an upper arch member 11, a pair of opposed side frames 12 and 13, and a bed 14, the several parts of the frame being interconnected rigidly with one another by means of four vertical through bolts or rods 15, shown in Fig. 3.

In the upper portion of the press is a slide 17, adapted to operate as a blank holder, this slide being guided for vertical reciprocatory movement in guides 18 provided on the frame sides 12 and 13. Within the slide 17 is a second upper slide 19, adapted to operate with a dwell in its movement in timed relationship with the operation of the blank holding slide 17. The two slides 17 and 19 are each operated by a set of toggle arms and connections therefrom to an operating or crank shaft 20 which is rotatably mounted in the press frame in suitable bearing 21, indicated in Fig. 2.

The operating connection between the crank shaft 20 and the blank holder slide 17, as illustrated in Figs. 1, 7, and 9, comprises a pair of parallel rock shafts 23 and 24, each mounted for oscillatory rocking movement in bearings 25 provided in the arch of the press. The two rock shafts are of irregular form, as shown in Fig. 9, the rock shaft 24 including as a part thereof the toggle arms 26 and 27 to which are pivotally connected the toggle links 28 and 29 respectively. The lower ends of the links 28 and 29 are pivotally connected to adjustable bracket members 30 which are vertically adjustable in the corner portions of the slide 17. Similarly arranged toggle arms 31 and levers 32 connect the opposite or rear portion of the slide 17 to the rock shaft 23 as indicated in Fig. 7.

At the center portion of each of the rock shafts 23 and 24 are projecting arms 33 and 34 respec-

tively, which are pivotally connected to and operated by the two links 35 and 36. These, in turn, are pivotally connected to a double armed lever 37. The double armed lever 37 is suitably fixed to a short shaft 38 which is rotatably journaled in bearings 39 in the arch 11. As will be apparent from Fig. 7, the connections from the opposite ends of the lever 37 are symmetrically disposed with respect to the two rock shafts 23 and 24 so that movement of the lever 37 will cause similar and equal rocking movements of the two rock shafts in the same direction.

The double armed lever 37 has a downwardly projecting end 40 which is pivotally connected to a link 41, pivoted in turn on the end of a rock lever 42, the supporting shaft 43 of which is provided in a bracket portion 44 of the press frame. Pivotally connected to the lever 42 is the crank pitman 45, the opposite end of which is mounted on a crank 46 provided centrally on the crank shaft 20. The center of the crank shaft is thus connected by a simple system constituted entirely of links and rock members or arms to the two toggle shafts 23 and 24, the dead center positions of the various axes and link connections being arranged for simultaneous alignment to provide a large dwell period for the slide 17, as indicated by the curve 17A in Fig. 8. Fig. 7 shows the various positions of the parts when the slide 17 is in its uppermost position, it being apparent that 180° counter-clockwise movement of the crank shaft, as viewed in Fig. 7, causes the rock shafts 23 and 24 to move about 90 degrees and bring the slide 17 to its lowermost position.

The slide 19 is operated by toggle links 48 and 49 at the front portion of the press, these links being pivotally connected respectively to rock members 50 and 51 which are journaled for rocking movement in the rock shaft 24. The axis about which the rock members 50 and 51 are movable coincides with the axis of the rock shaft, the latter having an offset hood-like portion 52 near each end thereof affording a space in which a rock member is mounted, as by means of the stub shaft 53 which is journaled in suitable socket portions 54 provided in the rock shaft. The two rock members 50 and 51 at the front of the press are, therefore, capable of movement independently of the movements of the rock shaft 24 in which they are journaled, the hood-like portions 52 of the rock shaft serving to interconnect the central or body portion of the rock shaft and the end portions on which the arms 26 and 27 are provided. The rear portion of the slide 19 is similarly connected to a pair of toggle links 57 one of which is indicated in Fig. 6, the toggle links 57 being pivoted to individual rock members 56 which are independently journaled in the rock shaft 23 within the hood-like portions 58 of that rock shaft.

The two rock members 50 and 56 which are provided respectively at the front and at the rear of the left-hand side of the press, as viewed in Fig. 1, are operated similarly in the same direction, independently of any direct connection to the rock shafts 23 and 24, by means of a double armed lever 60 one end of which is connected by a pivoted link 61 to the rock member 56 while the other end is connected by a pivoted link 62 to an extension 63 rigid with the rock member 50 and received in the hood-like portion 52 of the rock shaft 24. The double armed lever 60, which is mounted for rocking movement coaxially with the short shaft 63, journaled in bearings 64, 75 is provided with a downward extension 65 which

is pivotally connected to the upper end of the crank pitman 66 the other end of which is mounted for rocking movement on the crank 67 of crank shaft 20. As will be apparent from Fig. 6, counterclockwise movement of the crank shaft from the position shown, in which the slide is at its uppermost limit of travel, will move the double armed lever 60 clockwise through such angle as to cause about 90 degrees movement of the rock members 50 and 56, thus moving the slide 19 to its lowermost position of travel and causing a considerable dwell at the lower limit of travel by reason of the alignment of the links 61 and 62 with the axis of movement of the double armed lever and by reason of the alignment of the toggle arms and levers connected to the slide 19.

Mounted in the press frame and symmetrically arranged with respect to the disposition of the double armed lever 60 is a second double armed lever 68 as shown in Fig. 2, lever 68 being connected to a crank pitman 69 which has the same spacing from the center of the crank shaft as the crank pitman 66. The double armed lever 68 is connected to operate the rock member 51 and the correspondingly opposed rock member at the rear of the press in the same manner as illustrated in Fig. 6 so that the two double armed levers 60 and 68 are moved equally at the same time, and the four corners of the slide 19 are moved equally by a mechanism constituted entirely by pivotally connected links and arms or levers. Expensive motion transmitting slides with their carefully machined guides are therefore obviated, and a comparatively simple system is provided for symmetrically connecting the crank shaft in a balanced manner to the outer and inner slides 17 and 19 to give proper dwells to both of these slides so that the slide 17 can descend first and operate as a blank holding member during the time the slide 19 descends and performs suitable draw or forming operation. The relative timing of the operation of the slides 19 is indicated by the curve 19A in Fig. 8. The slide 17 reaches its lowermost position somewhat ahead of the slide 19, the crank 46 leading the crank 67 some suitable amount as indicated in Figs. 6 and 7 to provide the desired sequence in slide movements.

As shown in Fig. 1 fluid pressure cylinders 70 may be provided in the press frame for guiding piston elements connected as shown at 71 to the slide 17 for effecting a desired counterbalancing effect.

The crank shaft 20 is provided at each end with a gear 72. Each gear 72 meshes with a pinion 73 provided on either end of the transverse shaft 74 which is suitably journaled in end bearings 75 on the rear of the press frame, and journaled in an intermediate bearing 76, shown in Fig. 2. Adjacent the bearing 76 is a drive gear 77 which is fixed to the shaft 74 and operated in a suitable manner by a driving motor provided on the rear of the press. Opposite ends of the crank shaft are therefore driven equally and symmetrically from the source of power.

Just inside of each gear 72, the crank shaft is provided with an eccentric portion adapted for cooperating with an eccentric strap 78. Each eccentric strap has a main body portion and a head portion 79 which surrounds the eccentric on the crank shaft, the two portions being detachably fixed together by suitable bolts. The two eccentric straps 78 extend down along the outer sides of the press frame sides and are connected, as will be more fully described, to a lower die carrying slide designated generally by the 75

reference numeral 80. The power is therefore effectively transmitted in a symmetrical or balanced manner from the crank shaft to the lower slide as well as to the two upper slides, which are 5 all moved in proper timed relationship. The curve 80A in Fig. 8 indicates the relative timing of the slide 80 with respect to the slides 17 and 19.

The lower slide 80 is mounted for vertical reciprocating movement in an opening 81 in the 10 press bed 14. Removably supported in the press bed are one or more beams or walls 82 the end portions of which are vertically slidable in grooves or guides 83 with which the bed is provided. Near the end portion of the bed are additional beams 15 or walls 84 also vertically guided so they may be upwardly removed from the press bed. The sides of the press bed and the beams 82 and 84 are adapted for the support of a bolster plate 85, a portion of which is shown in Fig. 4. This bolster 20 plate may be provided with holes or openings through which the usual pins leading up to a lower die can be moved in accordance with the movement of the lower slide 80. The lower ends of the operating pins may be engaged and operated by the plate sections 86 which are vertically guided in the press bed and in the removable beams 82 and 84. In Fig. 3 one of these plate sections 86 is shown partially broken away to disclose one of the stools or blocks 87 one of which 30 is provided for the support of each of the plate sections 86. The several stools 87 are received on and secured to a pair of stool brackets 88 and 89 which are connected by bolts 92 to one another and to the central rib 90 of a main body member 35 91 of the slide 80. The total length of each of the stool brackets 88 and 89 is somewhat less than the distance between the side frame members 12 and 13 of the press so that the stool brackets can be taken off toward the front and rear of the 40 press as indicated in dotted lines in Fig. 5 when the lower slide is removed upwardly from the press bed, as will be more fully explained.

The main body part 91 of the lower slide is rather narrow as shown in Fig. 5, but has a 45 length exceeding the distance between the frame sides 12 and 13, as shown in Figs. 3 and 4, since the ends of this body member are operated by the eccentric straps 78 which extend down along the outer sides of the press frame. The press frame sides 12 and 13, however, are each provided with 50 an opening 93 which extends high enough up from the press bed, and which is wide enough in a horizontal direction, to accommodate the maximum height and width of the body portion 91 of slide 55 80 when the latter is removed upwardly from its normal position in the press bed. This arrangement greatly facilitates assembly and disassembly of the lower slide in the press bed, as it does not require a large space below the bed for the reception 60 of the lower slide when the latter is being removed from the bed. In accordance with the present invention when it is desired to remove the lower slide 80 as for replacement or repair purposes, the bolster plate 85 is removed from the bed 65 and the removable beams or walls 82 and 84 are withdrawn. The beam 94, which connects the body portion 91 to the pistons 95 operating in the counterbalancing fluid pressure cylinders 96 fixed on the bed, is then disconnected from the body portion 91. The connection between the eccentric straps 78 and the end portions of the slide 80 are also disconnected, for example, by first separating the bolted connection between the central portion of strap 78 and the upper 70 75 or eccentric portion 79 thereof. The slide is

then moved upwardly from its normal position in the bed of the press, the stools 87 and their upper plates 86 being taken off so that the upward movement of the slide 80 may be continued until the stool brackets 88 and 89 are positioned at a 5 level above the top of the press bed. These parts 88 and 89 are then disconnected from one another and from the rib 90 of the slide body and then withdrawn toward the front and back of the 10 press. This leaves the body portion 91 of the lower slide which is then moved up still further until its lower end projects above the top of the press bed. As its total width and height can be accommodated in the openings 93 in the sides 15 of the press frame, it is then a simple matter to move the body member 91 in the direction of its length and take it off entirely through the opening in one of the frame sides. In replacing the slide, the procedure above outlined is followed by a reverse order.

As herein shown, the normal limiting positions of movement of the lower slide may be adjusted, the lower end of each eccentric strap being connected pivotally to an adjustable post 98. The threads 99 on this post are engaged by internal 20 threads on a sleeve 109 which may be rotated by a bevel gear 101 which meshes with a bevel pinion 102. The bevel pinion 102 is driven by a suitable gearing including gear 103 having a 25 geared connection to a gear 104, geared in turn to a shaft 105 which extends across the front of the lower portion of the bed. The shaft 105 is turned by a suitable motor 106. The shaft 105 extends similarly to opposite sides of the press so as to operate the two bevel gears 101 at the same 30 time and similar amounts, so that the positions of the two adjustable posts 98 can be simultaneously adjusted with respect to the slide 80. In effecting removal of the lower slide from its normal housed position in the press bed the motor and the various 35 movable elements connecting the motor 106 to the eccentric straps 72 are taken off or disassembled so that the passage of the lower slide through the opening of the press bed and through the 40 openings in the frame sides can be readily 45 effected.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A drawing press comprising a frame, first and second die slides slidably mounted in said frame, toggle means for operating said first slide, toggle means for operating said second slide, a crank shaft rotatably mounted in said frame, means operably connecting said crank shaft at a point between its ends to one of said toggle means, and means entirely devoid of slide members and constituted entirely of pivotally connected arms and links operably connecting said crank shaft to the other of said toggle means.

2. A drawing press comprising a frame, first and second die slides slidably mounted in said frame, toggle means for operating said first slide, toggle means for operating said second slide, a crank shaft, toggle operating means connecting the crank shaft to one of said toggle means, toggle operating means connecting the crank shaft to the other toggle means, said toggle operating means both being entirely devoid of slide members and constituted entirely of pivotally con-

nected arms and links and both being symmetrically connected with respect to the center of the crank shaft.

3. A drawing press comprising a frame, first and second die slides slidably mounted in said frame, toggle means for operating said first slide, toggle means for operating said second slide, an operating shaft rotatably mounted in said frame, means operably connecting the center of said shaft to one of said toggle means, means entirely devoid of slide members and constituted entirely of pivotally connected arms and links operably connecting said shaft at points equally spaced from its center to the other of said toggle means, 15 a third die slide slidably mounted in said frame, and arms symmetrically connecting opposite end portions of said shaft directly to said third slide.

4. A drawing press comprising a frame, a crank shaft rotatably mounted in said frame, a die slide 20 slidably mounted in said frame, a pair of rock shafts rotatably mounted in said frame, toggle means connecting said rock shafts to said slide, an arm rigid with each rock shaft, a lever pivotally supported on the frame, a link connection 25 between said lever at opposite sides of the axis of pivotal support of the lever and extending to each of said arms, a second lever pivoted on said frame, a link connection between said levers, and an arm operably connecting said second lever to said 30 crank shaft.

5. A drawing press comprising a frame, a crank shaft rotatably mounted in said frame, a die slide slidably mounted in said frame, four individual rock members mounted in said frame, a 35 toggle connection between each rock member and said slide, a pair of levers oscillatably mounted in said frame, link connections between each lever and a pair of said rock members, and an operating connection between each of said levers and said 40 crank shaft and provided at equal distances from the crank shaft center.

6. A drawing press comprising a frame, first and second die slides slidably mounted in said frame and operating with dwells in their movements, a 45 pair of rock shafts mounted in said frame, a pair of toggle connections between each rock shaft and said first slide, a pair of rock members adjacent each rock shaft, a toggle connection between each rock member and said second slide, a 50 crank shaft rotatably mounted in said frame, means connecting the center of the crank shaft to both said rock shafts, a pair of oscillatable double armed levers mounted in said frame, means connecting each of said levers to said 55 crank shaft at points symmetrically spaced from the center thereof, and four links each connecting an end of one of said levers to one of said rock members.

7. A drawing press comprising a frame, first and second upper die slides mounted for reciprocating movement in said frame, a crank shaft rotatably mounted in said frame, toggle means for operating each of said slides, means entirely devoid of slide members and constituted entirely 65 of pivotally connected arms and links symmetrically connecting said crank shaft to both said toggle means, a lower die slide mounted for reciprocating movement in said frame, and arms extending downwardly from end portions of said 70 crank shaft and connected at their lower ends directly to said lower slide for reciprocating the same in timed relation with the movement of said upper slides.

8. In a drawing press, a frame, two die slides 75 movable in the frame towards effective positions

in the same direction relatively to the press, a pair of rock shafts mounted in said frame, a crank shaft rotatably mounted in said frame, an operating connection between said crank shaft and said rock shafts, toggle connections between said rock shafts and one of said slides, rock members concentric with said rock shafts and provided adjacent both ends of the rock shafts, operating means for said rock members connected to points symmetrically spaced from the center of said crank shaft and entirely devoid of slide members and constituted entirely of pivotally connected arms and links, toggle connections between said rock members and the other slide, a third die slide mounted in said frame and movable towards an effective position in a direction opposed to the movement of said first mentioned slides, and operating connections symmetrically connecting end portions of said crank shaft to said third slide.

9. A press comprising a frame having a bed and side frame members extending upwardly from said bed, an operating shaft rotatably mounted in an upper portion of said frame, an upper slide operated by said shaft, a lower slide movable in 25 the bed of the press, operating connections from end portions of said shaft to said lower slide, said lower slide having a length exceeding the distance between said frame members and said frame members having openings receiving end 30 portions of said lower slide, the lower slide being removable upwardly from said bed and having a long body portion removable in the direction of its length through one of said openings.

10. A press comprising a frame having a bed 35 and having opposed side frame members extending upwardly from said bed, a slide operably mounted in said bed and comprising a main body portion having a length greater than the distance between said frame members, said slide 40 being removable upwardly from said bed and said frame members having openings in which the ends of said body portion are receivable when said slide is removed upwardly from the bed, said body portion being removable in the direc- 45 tion of its length through one of said openings.

11. A press comprising a frame having a bed and having opposed side frame members extending upwardly from said bed, a slide operably mounted in said bed and comprising a main body 50 portion having a length greater than the distance between said frame members, means extending upwardly along the outer sides of said frame members for operating said slide, said frame members having openings in which the ends of 55 said body portion are receivable when said slide is removed upwardly from the bed and through which the body portion is endwise removable from the press.

12. A press comprising a frame having a bed 60 and having opposed side frame members extending upwardly from said bed, a slide operably mounted in said bed, said slide having a main body portion defining the slide length and having a top portion removably fixed to said body portion 65 and removable from between the frame members of the press when the slide is raised up from the bed, said frame members having an opening at least as large in height and width as the height and width of said body portion through which 70 said body portion is endwise removable from the press.

13. In a press, a bed having a removable beam adapted to be withdrawn upwardly from said bed, a frame member extending upwardly from said 75

bed at one side thereof and having an opening therein, a slide mounted in said bed below said beam, said bed having an opening in which said slide is mounted and through which the slide can be withdrawn upwardly after removal of said beam, said slide having a body member defining the length of the slide and capable of endwise movement through the opening in said frame member, and driving means for said slide connected to an end portion thereof outwardly of the frame member.

14. A drawing press comprising a frame, first and second die slides slidably mounted in said

frame, toggle means for operating said first slide, toggle means for operating said second slide, a crank shaft rotatably mounted in said frame, all of said toggle means operating in planes transverse to the crank shaft axis, means operably connecting said crank shaft at a point between its ends to one of said toggle means, and means entirely devoid of slide members and constituted entirely of pivotally connected arms and links operably connecting said crank shaft to the other 10 of said toggle means.

ARTHUR A. BYERLEIN.
